Primary Examiner — Kevin K Rudzinski*(74) Attorney, Agent, or Firm* — Banner & Witcoff, Ltd.(57) CLAIM

The ornamental design for a sports shirt with label, as shown and described.

DESCRIPTION

FIG. 1 is a front left perspective view of a sports shirt with label showing our new design;

FIG. 2 is a front view thereof;

FIG. 3 is a front right perspective view thereof; and,

FIG. 4 is an enlarged detailed view of the label shown in FIGS. 1-3.

The broken lines immediately adjacent to the shaded area define the bounds of the claimed design and form no part thereof. The broken lines representing alphanumeric content represents illustrative content which forms no part of the claimed design. The two broken line rectangles represent unclaimed regions and form no part of the claimed design. The broken lines showing the remainder of the sports shirt represent unclaimed subject matter and form no part of the claimed design.
